[57] CLAIM

The ornamental design for a cordlock for raisable blind, as shown.

DESCRIPTION

FIG. 1 is a top, front and right side perspective view of a cordlock for a raisable blind showing my new design; FIG. 2 is a bottom and left side perspective view thereof;

FIG. 3 is a top plan view thereof;

FIG. 4 is a rear elevational view thereof; and,

FIG. 5 is a front elevational view thereof.

The broken line showing of the pleated blind assembly in FIGS. 1 and 5 is for illustrative purposes only and forms no part of the claimed design.

FIG. 1

FIG. 3

FIG. 2

FIG. 4

FIG. 5
